CHARLES L. GOODRUM, OF NEW YORK, N. Y., ASSIGNOR BY MEENE ASSIGNMENTS, TO
WESTERN ELECTRIC COMPANY, INCORPORATED, A CORPORATION OF NEW YORK.

MACHINE-SWITCHING TELEPHONE-EXCHANGE SYSTEM.

1,251,504.

Specification of Letters Patent.

Patented Jan. 1, 1913.

Application filed August 23, 1915. Serial No. 46,890.

To all whom it may concern:

Be it known that I, CHARLES L. GOODRUM, a citizen of the United States, residing at New York, in the county of New York and State of New York, have invented certain new and useful Improvements in Machine-Switching Telephone-Exchange Systems, of which the following is a full, clear, concise, and exact description.

10 This invention relates to telephone exchange systems employing machine switching. It is the practice to signal a wanted party by intermittently ringing the bell at his substation. This is done automatically by a ringing machine at the connector, such machine having a commutator on the shaft or equivalent means for breaking the call up into short rings. It frequently happens that connection is made with a wanted line during what is known as a silent interval; that is, while the open circuit part of the commutator is connected with the called party's line.

25 A feature of this invention consists in providing means associated with the connector for instantly applying current from a ringing generator to the called line when the connector is set thereon. In case the subscriber responds to this signal, ringing current is cut off by a marginal relay in the ringing circuit. However, if not, ringing current is intermittently applied to the line through an interrupter until the called party responds, and operates the marginal relay, or until the calling party hangs up his receiver and restores the connector.

30 In the present embodiment of the invention this result is secured by providing a slow-acting relay located in a circuit in parallel with the secondary stepping magnet of the connector. Consequently, the impulses sent to the secondary stepping magnet to set the connector on the called line also pass through the said slow-acting relay. This 35 relay at its armature and front contact controls the connection of the ringing generator with the called line, and being slow, holds up its armature for an interval after the brushes connect with the selected line and the side switch is released into the ringing position to ring the bell thereat. If the 40 line is busy, however, the connector is restored before the side switch is released into the ringing position. Upon the deenergization 45 of this relay, it connects at its armature

and back contact the ringing generator, through an interrupter and marginal relay, with the called line. Thus, in case the called subscriber does not answer immediately, his bell is intermittently rung until he responds and operates the marginal relay to cut off the ringing current.

50 The invention will be more readily understood when described with reference to the accompanying drawing. For simplicity, the connector circuit only is shown, it being understood that a connection would ordinarily lead from the calling substation A through one or more finders and group selectors, and finally through the connector shown to the 55 called substation B. When the calling line has been extended through to the connector, therefore, the stepping relay 10 thereat is energized over the following circuit: free pole of battery, left winding of relay 10, selector contact 11, selector brush 12, finder brush 31, finder terminal 33, through the telephonic apparatus at substation A over the line conductors *a*, *b*, finder terminal 32, finder brush 30, selector brush 13, selector 60 contact 14, right winding of relay 10 to ground. Relay 10 at its armature and front contact energizes the slow relay 15. Relay 15 at its right armature and front contact prepares a circuit for a second slow 65 relay 16.

70 The calling subscriber now operates the sender S in transmitting the tens digit of the wanted line. Upon the first deenergization of the line relay 10, slow relay 16 is 75 energized. This relay at its inner armature and front contact energizes a slow magnet 17, which is the side switch escapement magnet and which is arranged to release the side switch from position to position only upon 80 its deenergization. Each time the relay 10 closes its front contact, an impulse is sent to primary magnet 18 by way of side switch arm 3 and the right armature and front contact of magnet 17, to position the brushes 85 20, 21, 22 in operative relation to the group containing the terminals 23, 24, 25 of the wanted line. When the sender S restores at the end of tens selection, the line relay is 90 maintained energized, and consequently the 95 relay 16, after an interval, retracts its armatures. The retraction of its inner armature opens the circuit of escapement magnet 17, which after an interval retracts its armatures, releasing the side switch into position 100 110

2. The calling party now operates his sender S in transmitting the units digit of the wanted line. Upon the first deenergization of the line relay 10, the slow relay 16 is again energized, and at its inner armature and front contact again energizes the escapement magnet 17. Each time the armature of relay 10 closes its front contact, an impulse is sent to the secondary stepping magnet 19 by way of arm 3 and the right armature and front contact of magnet 17, thus stepping the wipers 20, 21, 22 over the terminals 23, 24, 25 of the selected group. Upon the termination of units selection, the sender S restores and maintains the line relay energized, as before. Consequently, the slow relay 16 after an interval retracts its armatures. The retraction of the inner armature opens the circuit of escapement magnet 17, but inasmuch as this magnet is slow-acting, it does not release the side switch instantly. If the selected line, upon whose test terminal 25 the test brush 22 is now resting, is busy, such terminal 25 will be grounded, and, consequently, the following circuit is closed to the release magnet 26 of the connector before the escapement magnet deenergizes sufficiently to release the side switch: free pole of battery, magnet 26, armature and back contact of relay 27, primary off-normal spring 28, outer armature and back contact of relay 16, arm 1, test brush 22 to grounded test terminal 25. Magnet 26 at its right armature and front contact locks itself over the following path: free pole of battery, magnet 26, right armature and back contact of relay 27, resistance 29, right armature and front contact of magnet 26, left armature and front contact of relay 15, armature and back contact of relay 30 to ground. Magnet 26, at its left armature and front contact, connects the busy-back apparatus 31 to conductor 32, indicating to the calling party at substation A that the desired line is busy. When such party restores his receiver, the line relay 10 is deenergized which causes the relay 15 to be deenergized. This relay, in retracting its left armature, opens the locking circuit of magnet 26. The retraction of the left armature of magnet 26 disconnects the busy-back apparatus from connection with conductor 32. The retraction of the right armature of relay 15 grounds conductor 33 leading back to the preceding switches to release the same.

If the selected line is idle, the test terminal 25 thereof is not grounded. Consequently, at the end of units selection the deenergization of relay 16, due to the maintained energization of relay 10, causes the escapement magnet 17 to become deenergized to release the side switch into position 3. In position 3, arm 1 grounds test terminal 25, thus causing this line to be unselectable to

other testing connectors or finders. In position 3, the following circuit is closed for the escapement magnet 17: free pole of battery, magnet 17, arm 2 and its third contact, left armature and front contact of relay 70 15, armature and back contact of relay 30 to ground. In position 2, impulses were sent to a slow relay 34 in a circuit in parallel with the circuit to the secondary stepping magnet 19 as follows: free pole of battery, 75 relay 34, arm 3 and its second contact, right armature and front contact of magnet 17, armature and front contact of relay 10 to ground. This relay 34 is arranged to hold its armature attracted for an interval after 80 its circuit is opened at side switch arm 3 and its second contact when the side switch moves out of position 2. Consequently, the following circuit is closed to give an initial short signal to the called party: free pole 85 of ringing generator 35, armature and front contact of relay 34, relay 30, left armature and front contact of magnet 17, arm 4, brush 21, terminal 24, line conductor 'a', bell 37, condenser 38, line conductor 'b', terminal 23, 90 brush 20, arm 5 to ground. Upon the retraction of the armature of relay 34, the following circuit is closed to ring the bell 37 intermittently: free pole of ringing generator 35, interrupter 36, armature and back contact of relay 34, relay 30, through the bell 37 at substation B, to ground over the circuit just traced. When the party at substation B removes his receiver in answering the call, relay 30 which is marginal responds 100 in the well-known manner. By attracting its armature it opens the circuit traced for the escapement magnet 17 which releases the side switch into position 4, thus opening the ringing circuit. In position 4 a circuit is 105 closed for the called supervisory relay 27, leading over arm 4 and its fourth contact, brush 21, terminal 24, through the telephonic apparatus at substation B, terminal 23, brush 20, arm 5 and its fourth contact, right 110 winding of relay 27 to ground. Talking battery is now fed to the calling party over the windings of relay 10 and to the called party over the windings of relay 27. When the calling and called parties hang 115 up their receivers, the following circuit is closed for the release magnet 26 to release the connector and restore the side switch: free pole of battery, magnet 26, right armature and back contact of relay 27, primary 120 off-normal contact 28, left armature and back contact of relay 15, armature and back contact of relay 30 to ground. The retraction of the armature of relay 10 and the right armature of relay 15 grounds conductor 33 125 leading back to the preceding switches to release the same.

What is claimed is:

1. In a telephone exchange system the combination with telephone lines, a connec- 130

tor switch wherein said lines terminate, a ringing current generator associated therewith, an interrupter normally in circuit with said generator, and means for setting said connector switch on said lines, of means operated due to the connector switch being set on a selected line for instantly applying ringing current from said generator to said line irrespective of the position of said interrupter, and a relay arranged to disconnect said generator from said line upon the response of the called party.

2. In a telephone exchange system the combination with telephone lines, a connector switch wherein said lines terminate, a ringing current generator associated therewith, an interrupter normally in circuit with said generator, and means for setting said connector switch on said lines, of means operated due to the connector switch being set on a selected line for instantly connecting said generator direct to the selected line independently of said interrupter, and a relay arranged to disconnect said generator from said line upon the response of the called party.

3. In a telephone exchange system the combination with telephone lines, a connector switch wherein said lines terminate, a stepping magnet for setting said switch on said lines, a stepping relay arranged to transmit impulses to said stepping magnet, a ringing generator associated with said connector switch, and an interrupter normally in circuit with said generator, of a slow relay in circuit with said magnet for directly connecting said generator to the selected line as soon as the connector switch is set thereon to instantly connect ringing current thereto irrespective of the position of said interrupter.

4. In a telephone exchange system the combination with telephone lines, a connector switch wherein said lines terminate, a stepping magnet for setting said switch on said lines, a stepping relay arranged to transmit impulses to said stepping magnet, a ringing generator associated with said connector switch, and an interrupter normally in circuit with said generator, of a slow-acting relay in parallel with said magnet for

directly connecting said generator to the selected line as soon as the connector switch is set thereon to instantly connect ringing current thereto irrespective of the position of said interrupter.

5. In a telephone exchange system, the combination with telephone lines, a connector wherein said lines terminate, a stepping magnet for setting the same on said lines, a stepping relay adapted to deliver impulses to said stepping magnet, a ringing generator associated with said connector, and an interrupter normally in circuit with said generator, of a slow-acting relay in parallel with said magnet and adapted to connect said generator without said interrupter to the selected line at its armature and front contact, and at its armature and back contact to connect said generator with said line through said interrupter.

6. In a telephone exchange system, the combination with telephone lines, a connector wherein said lines terminate, test terminals for said lines in said connector, a stepping magnet for setting the same on said lines, a stepping relay adapted to deliver impulses to said stepping magnet, a sender adapted to intermittently operate said stepping relay, a slow relay 16 adapted to be maintained energized during the operation of said sender, a side switch controlling said connector, a slow-acting escapement magnet 17 therefor, a circuit for said escapement magnet controlled at an armature and front contact of said slow relay, a release magnet for said connector, a circuit therefor controlled at an armature and back contact of said slow relay, means for grounding the test contacts of busy lines, a ringing generator associated with said connector, of a slow-acting relay 34 in circuit with said stepping magnet and controlling the connection of said generator with the selected line, whereby if the line is busy the circuit of said release magnet is closed, and if the line is idle said generator is instantly applied to said line for a short interval.

In witness whereof, I hereunto subscribe my name this 18th day of August A. D., 1915.

CHARLES L. GOODRUM.
